WITNESSES:

UNITED STATES PATENT OFFICE.

AUGUST F. BEITZELL AND CHARLES B. WHELTLE, OF BALTIMORE, MARYLAND.

SHIP PROPULSION.

Application filed April 18, 1922, Serial No. 554,809. Renewed October 21, 1925.

To all whom it may concern:

Be it known that we, AUGUST F. BEITZELL and CHARLES B. WHELTLE, citizens of the United States, residing at Baltimore, in the county of Baltimore City and State of Maryland, have invented new and useful Improvements in Ship Propulsion, of which the following is a specification.

The general object of this invention is to provide means for producing power from the movement of a ship through the water, said power being used for various purposes, such as running machinery on the ship.

Another object of the invention is to provide electric means for driving the ship and an engine for actuating the electric generator, with means for connecting the propeller shaft to the motor, when desired.

A further object of the invention is to provide transmission means for the various parts for increasing or decreasing the speed of the driven member by the driving member.

This invention also consists in certain other features of construction and in the combination and arrangement of the several parts, to be hereinafter fully described, illustrated in the accompanying drawings and specifically pointed out in the appended claims.

In describing the invention in detail, reference will be had to the accompanying drawings wherein like characters denote like or corresponding parts throughout the several views, and in which:—

Figure 1 is a diagrammatic plan view showing the application of our invention.

Figure 2 is a diagrammatic view showing a modification of the invention.

In these views 1 indicates the shaft for the driving propeller 2 of the ship which is connected with the electric motor 3 through the transmission means 4, such means being hereinafter described. A generator 5 has its shaft aligned with the motor shaft and the two shafts are adapted to be connected together by the clutch means 6. The generator is actuated by an internal combustion motor 7, the shaft of which is connected with the generator shaft by the gears 8 and 9 on the said generator and motor shafts and the gears 10 on the shafts 11. Clutch means 12 are provided for the motor shaft and the gears are all arranged in the gear housing 13.

It will thus be seen that the generator can

be driven from the motor 7 to furnish current for the motor 3 and the movement of this motor 3 is transmitted to the propeller by means of the transmission means 4. By means of the clutch 6, if anything should happen to the electric driving means the propeller shaft can be driven from motor 7 by placing the clutch 6 in operative position. This clutch is normally in disengaged position.

In order to utilize the movement of the ship through the water to produce power we provide a pair of propellers 14, the shafts 15 of which are arranged parallel to the shaft 1. These shafts 15 are connected by the transmission means 16 with the generators 17, clutches 18 being interposed between the generators and the transmission means. These generators 17 can be connected with shafts 19 by the clutches 20, said shafts 19 extending into the gear housing 13 where they are provided with the gears 21 which mesh with the large gears on shafts 11. The propellers 14 are actuated by the movement of the ship through the water and this movement is transmitted to the generators 17 by the transmission means 16. Thus electric current is produced by the passage of the ship through the water and this current can be used for various purposes about the ship. If desired it may be used to help run the motor 3. By means of the clutches it will be seen that the various elements can be connected or disconnected from the other elements, thus permitting repairs to be made and the ship to be run by the electric motor or the internal combustion motor.

The shafts are provided with the fly-wheels 22 and the clutches are operative in any desired manner.

From the above it will be seen that when power is applied to one end of the transmission means it will be communicated to the other end at a greater speed and vice versa. The drawing shows the transmission means being arranged to drive the propeller shaft 1 at a reduced speed and the transmission means 16 arranged to transmit the movement of the propellers 14 to the generator 17 at an increased speed.

In Figure 2 the propeller shaft 11 extends into a gear housing 40 and the part of the shaft in this housing is provided with a pair of gears 41 which mesh with two pair of gears 42 and 42'. The gears 42 are carried

by a shaft 43 and the gears 42' by a shaft 44. Shaft 43 is bolted by the flanges 45 to the shaft of the motor 46 and shaft 44 is bolted by means of the flanges 47 to the shaft of the motor 48. We provide reserve motors 49, the shafts of which may be connected by bolts and flanges 50 with the shafts 43 and 44. These motors are used if anything should happen to the motors 46 and 48, it being understood that the bolts are removed from the flanges 45 and 47 and the flanges 50 bolted together. The motors 46 and 48 are connected by bolts passing through flanges 51 with the shafts of generators 52 and said generators 52 have their shafts connected by bolts passing through the flanges 53 with the gear shafts 54 which project from the gear casing 55. A gear 56 is placed on each of the shafts 54, within the casing, and each gear 56 is connected by the gears 57 on shafts 58 with a gear 59 located on the shaft 60 of a gas motor 61. Normally the flanges 51 are not bolted together and current is supplied to the motors 46 and 48 from the generators 52 or current can be supplied to the reserve motors 49 from said generators. These generators are driven from the gas motors 61 through the gearing and shafting described. The propeller shaft 11 has its parts connected together by the low speed transmission means 62 and said shaft is provided with a fly-wheel 63. The shaft 64 of each of the propellers 65 is provided with a fly-wheel 66 and high speed transmission means 67 connects the two parts of the shaft 64 together. The shaft of each generator 68 is adapted to be connected with each propeller shaft by clutch means 69 and the shaft of each generator is adapted to be connected by the clutch means 70 with a gear shaft 71 projecting from the gear casing 55 and which is provided with a gear 72 which is connected by the gears 73 on shafts 74 to a gear 75 carried by the shaft of the gas motor 76. Thus each generator 68 is driven by the gas motors 76 through the shafting and gearing shown or each of said generators can be disconnected from its gas motor and connected with the propeller shaft 64 so that the movement of the ship through the water will actuate the propellers 65 and thus operate the generators to produce current which may be used for different purposes about the ship. We also provide gears 78 which are slidably mounted on shaft 79 and which are provided with suitable means for moving them into and out of

engagement with the large gears of the trains of gearing so that a pair of motors can be connected up to the shaft of each generator 52 or to each generator 68.

From the above it will be seen that by means of the flanges and clutches shown the main propeller can be driven by either pair of electric motors and if these motors should fail the main propeller can be driven by two of the gas motors or by all four of the gas motors by shifting the gears 78 and connecting the various shafts together.

It is thought from the foregoing description that the advantages and novel features of the invention will be readily apparent.

We desire it to be understood that we may make changes in the construction and in the combination and arrangement of the several parts, provided that such changes fall within the scope of the appended claims.

What we claim is:-

1. In combination with a ship, a driving propeller therefor, an electric motor for driving the same, an electric generator for the motor, clutch means for connecting the shaft of the generator with the shaft of the motor, an internal combustion motor, gears connecting the same with the shaft of the generator, a second generator, a shaft, clutch means for connecting said shaft with the shaft of the second generator, a gear connecting said shaft with one of the first mentioned gears, a propeller adapted to be driven by the passage of the boat through the water and means for communicating the movement of said propeller to the second generator.

2. In combination with a ship, a main propeller, a pair of auxiliary propellers, electric motors connected with the shaft of the main propeller, generators, means for connecting and disconnecting said generator shafts with the motor shafts, a generator for each auxiliary propeller shaft, means for connecting and disconnecting said generator with said shaft, a gas engine associated with each generator, gears connecting the engine shafts with the generator shafts, means for connecting and disconnecting said generator shafts with the gears and movable gears for connecting the gears of one gas engine with those of another gas engine.

In testimony whereof we affix our signatures.

AUGUST F. BEITZELL.
CHARLES B. WHELTLE.
